UNITED STATES PATENT OFFICE.

CHARLES A. WHITE, OF BOSTON, MASSACHUSETTS, AND ERNEST R. HUNTER, OF SOUND BEACH, CONNECTICUT.

METRONOME.

No. 923,094.

Specification of Letters Patent.

Patented May 25, 1909.

Application filed October 20, 1908. Serial No. 458,731.

To all whom it may concern:

Be it known that we, CHARLES A. WHITE and ERNEST R. HUNTER, citizens of the United States, residing at Boston, Suffolk county, State of Massachusetts, and Sound Beach, Fairfield county, State of Connecticut, respectively, have invented certain new and useful Improvements in Metronomes, of which the following is a specification.

10 This invention relates to improvements in metronomes.

The object of our invention is to provide a new and improved metronome which is simple in construction, compact, composed of 15 few parts, not apt to get out of order and can readily be adjusted to conform in its beats with the beats of a conductor or the time of a piece of music being performed and when so adjusted indicates the time at which the 20 musical piece is performed, on a scale commonly known as the Maelzel metronome scale, that is, so many beats per minute.

In the accompanying drawings, in which like letters of reference indicate like parts in 25 all the figures:—Figure 1 is a face view of our improved metronome. Fig. 2 is a transverse sectional view on the line $x-x$ of Fig. 1. Fig. 3 is a horizontal sectional view on the line $y-y$ Fig. 2. Fig. 4 is a horizontal sectional view on the line $z-z$ of Fig. 2. Fig. 5 is a side view parts being broken away and others shown in section. Fig. 6 is a detail view.

In the specific construction of the metronome shown in the drawings, for the purpose of illustrating the invention the metronome is made in the form of an ordinary watch and of the general appearance of a watch. The dial A is provided with a circle B of sub- 35 divisions from left to right from 40 to 208, these sub-divisions gradually increasing in size as shown. The dial is provided with four equi-distant marks on indicators C concentric with the circle B which indicators C 40 are separated one quarter of a circle from each other. A hand D rotates over the circle containing the indicators C and a larger hand E rotates over the circle B.

The device is contained in a suitable casing 50 like a watch case. The casing contains a spring barrel F provided with a key arbor F¹ carrying a ratchet wheel F² engaged by a spring pawl F³. A cog wheel F⁴ on the rim

of this spring barrel engages a pinion F⁵ on the same shaft with a cog wheel F⁶ and this 55 cog wheel F⁶ engages a pinion F⁷ on an arbor F⁸ to which is attached a disk F⁹ having upwardly extending pins F¹⁰ which extend into the underside of a disk G which is also held in place on the disk F⁹ by a central screw G¹. 60 A train of gearing G² driven from the arbor F⁸ operates an escapement G³ of any well known construction, the particular construction of which forms no part of the present invention. 65

The plate G is provided on its upper surface throughout with a series of radial grooves or corrugations a which can be engaged by a toothed wheel H mounted to rotate with and to slide lengthwise on a 70 squared shaft H¹ the ends of which are mounted in bearings H² slidably mounted in vertical guides H³ containing springs H⁴ that press the shaft H¹ downward and thus keep the toothed wheel H in contact with the 75 grooved or corrugated surface of the disk G. The wheel H is provided with a grooved hub which is mounted in a lug or wing H⁵ on one end of a bar J to slide in a suitable guide J¹, this bar being provided with an upwardly 80 extending rack J² which is engaged by a toothed wheel J³ on a shaft J⁴ suitably mounted and terminating in the crown J⁵ mounted in the conventional manner, as shown, for example in Fig. 1, so that by 85 turning this crown the bar J can be moved lengthwise in one direction or the other. The bar J is provided with a horizontal rack J⁶ as shown in Figs. 3 and 5, engaging a pinion K on a central arbor L supported at its 90 lower end by a bracket plate L¹ of the supporting frame J¹. A toothed wheel M of less diameter than the wheel H is fixed on the squared shaft H¹ and engages a toothed wheel N on the horizontal arbor N¹ mounted 95 in one of the guides H³, which arbor N¹ carries at its end a hub N² provided with two diametrically opposite radial fingers N³ which can engage the four prongs O of a wheel O¹ fixed on a sleeve O² mounted 100 loosely on the arbor L.

R is a push pin for lifting one end of the shaft H¹ for the purpose of disengaging the wheel H from the disk G.

S is the stop pin and starting lever.

105

The operation is as follows:—The move-

ment is started whereby the disk G is rotated and by the engagement of the wheel H with the disk G the shaft H' is rotated from it by means of the wheels M and N, the shaft N' is 5 rotated causing the fingers N² on the hub N' to rotate the sleeve O² which carries the hand D thus causing the same to make beats equal to one quarter of a circle. When the wheel H is nearer the circumference of the disk G it 10 will be rotated at a higher rate of speed than when the disk H engages the disk G nearer the center and thus the beats of the hand D will be of greater speed when the disk H is nearer the circumference of the disk H than 15 when it is nearer the center of the disk G. By turning the arbor J⁴ by means of the crown J⁵ the wheel H can be adjusted to be nearer the circumference or center of the disk G, as may be desired. Before making 20 such adjustment however it is preferable to press the button R so that the disk H will be thrown out of engagement with the disk G while such adjustment is made. The user takes notice of the beats of a conductor of an 25 orchestra or player and by turning the arbor J⁴ adjusts the disk H on the disk G until the beats of the hand D coincide with the beats of the conductor or player. By turning the arbor G⁴ the bar J is moved lengthwise in one 30 direction or the other as the toothed wheel J³ on the arbor J⁴ engages the rack J² on the bar J and as said plate is shifted lengthwise it turns the toothed wheel K on the arbor L thus changing the position of the hand E on said 35 central arbor L. When the operator thus adjusts the hand D so as to correspond to the beats of the conductor or player, he at the same time shifts the hand E and the hand E will point to a certain subdivision of the 40 circle B indicating the time for playing according to the numbers of the Maelzel metronome, for example, if the hand D has been adjusted to coincide with the beats of a conductor, the hand E will show at what 45 speed according to the Maelzel metronome, the music is being performed. After the desired information has thus been obtained, the movement can be stopped and can start at any subsequent time to verify the former 50 observations or to obtain observations at some other time of playing.

Having described our invention what we

claim as new and desire to secure by Letters Patent is:

1. In a metronome, the combination with 55 two scales, one having a uniform sub-division and the other having sub-divisions gradually increasing in size, of an indicator for each scale, a watch movement for moving the indicator that indicates on the equally divided 60 scale, manually actuated mechanism for shifting the other indicator, and a connection between the manually actuated mechanism for shifting one indicator and the watch movement, which connection varies the 65 speed of the watch movement while shifting the hand not operated by the watch movement, substantially as set forth.

2. In a metronome, the combination with 70 a dial having two scales, of a movable indicator for each scale, a watch movement for moving one of the indicators, which watch movement comprises an escapement of conventional construction, and which movement has means independent of the escapement, 75 for varying the number of its beats per minute, mechanism for adjusting said beat varying means and an indicator connected with the mechanism for adjusting said beat varying means, substantially as set 80 forth.

3. In a metronome, the combination with 85 a dial having two scales, of an indicator for each scale, a watch movement for moving one indicator over its scale, which watch movement comprises a conventional escapement an adjustable and varying beat producing means in such a watch movement, independent of the escapement, mechanism for adjusting said beat producing means, means 90 for operating said adjustable mechanism from the exterior of the movement and a hand connected with the mechanism for adjusting the beat producing means, substantially as set forth. 95

In testimony whereof, we have signed our names to this specification in the presence of two subscribing witnesses, this 6th day of April, 1908.
